(57) **CLAIM**

The ornamental design for a mammography equipment, as shown and described.

DESCRIPTION

FIG. 1 is a top, front and right side perspective view of a mammography equipment showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof;

FIG. 7 is an enlarged top, front and right side perspective view of an operation button included in FIG. 1;

FIG. 8 is an enlarged right side elevational view of an operation button included in FIG. 6;

FIG. 9 is a cross-sectional view thereof taken along line IX-IX of FIG. 6 and a portion defined by an arrow A and an arrow B of FIG. 4, in which an internal structure thereof is not shown; and,

FIG. 10 is a cross-sectional view thereof taken along line X-X of FIG. 4 and a portion defined by an arrow A of FIG. 4 and an arrow C of FIG. 6, in which an internal structure thereof is not shown.

The broken lines showing the portions of the mammography equipment in all views shown represent unclaimed subject matter and form no part of the claimed design.

The two-dot chain lines in FIGS. 1,6,7,8 represent the boundary lines of the partially enlarged range and form no part of the claimed design.
